INVENTOR-

Herbert E. Enslin
By his Attorney,
Nelson M. Edwards

UNITED STATES PATENT OFFICE.

HERBERT E. ENSLIN, OF MALDEN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SKIVING-MACHINE.

1,358,140.

Specification of Letters Patent. Patented Nov. 9, 1920.

Application filed May 8, 1917. Serial No. 167,331.

To all whom it may concern:

Be it known that I, HERBERT E. ENSLIN, a citizen of the United States, residing at Malden, in the county of Middlesex and State of Massachusetts, have invented certain Improvements in Skiving-Machines, of which the following description, in connection with the accompanying drawings, is a specification, like reference characters on the drawings indicating like parts in the several figures.

This invention relates to skiving machines and is herein illustrated in connection with a machine of the general type shown in patent to Bayley No. 823,578 granted June 19, 1906.

In machines of this type the stock is fed by a feed roll having a substantially horizontal axis and a feed disk having a substantially vertical axis to a rotary disk knife the axis of which is inclined. The margin of the stock is gripped between the lower face of the feed disk and the periphery of the feed roll, being guided in its movement by a stationary edge gage. Between the edge gage and the adjacent point on the periphery of the feed disk there is a space the extent of which depends upon the width of the scarf to be produced; and in order to hold the stock down on the feed roll so as to produce a smooth scarf, a presser foot bridges this space, said presser foot being carried at one end of a leaf spring, the other end being fast to a stationary part of the machine. With this construction the following disadvantageous result is liable to occur. The edge of the stock at times crowds up against the edge gage and curls up or over upon itself underneath the presser so that when this curled up or over portion reaches the knife a gouge is produced in the edge or margin of the stock. Moreover, when the stock has once become pushed against the edge gage and the edge of the stock curled up or over in the manner described above, the grip of the feed disk and feed roll prevents the stock from backing away from the edge gage and thereby straightening out so as to lie properly in place.

One feature of the present invention comprises, in a machine of the class described, a knife, an edge gage, a plurality of members constructed and arranged to grip the

stock and feed it to the knife, and means responsive to the curling of the edge of the stock for loosening the grip of the feed members. In the illustrative machine a presser is attached to the feed disk so that whenever the presser is raised by the curled edge of the stock the feed disk is raised. This action may loosen the grip of the disk and roll enough to stop the feeding of the stock or merely loosen it sufficiently to permit the stock to move away from the gage until its edge lies flat as it should.

Hitherto the relative positions of the feed disk and feed roll have been such that a vertical plane through the axis of the feed roll either included the axis of the feed disk or was located slightly in the rear of the feed disk axis. Or to state the arrangement of parts in another way, the point on the feed disk, which at any given moment is nearest to the edge gage, is moving or is about to move away from said gage. The purpose of this arrangement has been to lessen the liability of the edge of the stock to crowd against the gage and thereby to be curled up or over in the manner which has been described above. This arrangement, however, has the disadvantage that it makes the guiding of the stock through the machine much more difficult than would be the case were the edge of the stock crowded against the gage continually. Another feature of the present invention comprises in a machine of the class described, a skiving knife, a feed roll, an edge gage, and means for crowding the edge of the stock against the gage during the feeding movement.

These and other features of the invention, including certain details of construction and combinations of parts will be described in connection with an illustrative machine and pointed out in the appended claims.

Referring now to the accompanying drawings,—

Figure 1 is an elevation of a machine in which the present invention is embodied, and

Fig. 2 is a plan of the feed disk, feed roll, edge gage and skiving knife, the knife being shown by a broken line.

The machine, like that of the patent to Bayley, which has been referred to, comprises a skiving knife 3, a feed disk 5 and a feed roll 7, the knife being driven by a belt

9 and the feed disk and feed roll by means of worms and gears, an upright shaft and bevel gears as shown. No further description of the details of the driving mechanism will be given since they are the same as those which are shown and described in the patent. It will be noted that in the present machine the inclination of the knife and the shape of the feed roll are different from the showing in the patent. This difference is due merely to the fact that the present machine is designed to produce a very narrow scarf at an angle of about forty-five degrees while the machine of the patent is designed to produce the usual scarf preparatory to folding the margin of a piece of leather.

The edge gage 9 of the machine is formed on one end of an arm 11 the other end of which is integral with a bracket 13 which is provided with a slot 15 through which and into the bearing block of the shaft of the feed roll passes a screw 17. By loosening this screw the bracket, and with it the edge gage, may be adjusted horizontally. The presser foot 19 is carried at one end of an arm 21, the other end of which surrounds the spindle 23 of the feed disk 5 and is held from vertical movement with respect to said spindle by a collar 25 fastened to the spindle by a set screw 27, the end of the arm 21 being held between the collar and an enlargement on the lower end of the spindle 23. Threaded into a socket in the arm 21 and held in adjusted position by a lock-nut 29 is a small post 31 the upper end of which is rotatable in a socket in a block 33 through which the spindle 23 loosely passes. A coiled spring 35 surrounding the stem 23 rests upon the block 33 and bears with its upper end against a part of the frame of the machine. By loosening the lock-nut 29 the post 31 may be turned to vary the tension of the spring and thereby to vary the force with which the feed disk and presser foot press the stock against the feed roll 7. The end of the edge gage 9 is provided with a vertical groove to receive a tongue 37 (see Fig. 2) on the end of the presser foot, this connection serving both to guide the presser foot in its vertical movement and to prevent the edge of the stock from riding over the edge gage. With this construction, if the edge of the stock becomes turned up or curled over the presser will be forced to rise and will carry the feed disk with it; and, according to the fixed vertical relation of the presser and disk will either stop the feeding of the stock or will permit the stock to slip away from the gage so as to allow the turned up or curled over portion of the edge to assume its proper position. In this connection it should be noted that by changing the position of the collar 25 on the spindle 23 the distance through which

the feed disk is raised by the presser may be varied.

Referring now to Fig. 2, there is shown the relation of the axis of the feed roll to that of the feed disk. The arrow indicates the direction of rotation of the feed disk; and it will be seen that the tendency of the construction and arrangement of parts is to crowd the edge of the stock against the edge gage and thereby to relieve the operator to a large extent from the necessity which formerly existed for guiding the stock.

The present machine, as has been stated, is designed to produce a very narrow scarf at a steep angle; and for this work it is desirable to crowd the edge of the work with considerable force against the edge gage. Consequently, in the illustrative machine the axis of the feed disk is located (see Fig. 2) at a considerable distance behind a vertical plane passed through the axis of the feed roll. It should be understood, however, that the extent of this distance and the angle of the scarf are not essential features of the present invention and that the invention in its broader aspects is not limited to the particular skiving machine or type of skiving machine which has been shown and described.

In the illustrative machine the feed roll is adapted to be adjusted toward the knife when the knife becomes worn. A certain amount of such adjustment is possible without disturbing essentially the relation of the axis of the feed roll to that of the feed disk. If, however, it is desired to maintain the relation of the axes exactly as shown, the knife may be made adjustable toward and from the feed roll as, for example, in the manner set forth in the patent to Amazeen No. 273,931 or Bayley No. 479,583. Inasmuch as such adjustment is old and well known, no showing or description of an illustrative construction, other than this reference to two patents will be given.

Having thus described my invention, what I claim as new and desire to secure by Letters Patent of the United States is:

1. A machine of the class described, having, in combination, a knife, an edge gage, a plurality of members constructed and arranged to grip the stock and feed it to the knife, and means responsive to the curling of the edge of the stock for loosening the grip of the feed members.

2. A machine of the class described, having, in combination, a knife, a plurality of members constructed and arranged to grip the stock and feed it to the knife, and a presser foot connected to one of said members in such manner that raising the foot loosens the grip of the members on the stock.

3. A machine of the class described, having, in combination, a knife, a plurality of members constructed and arranged to grip

the stock and feed it to the knife, a presser foot connected to one of said members in such manner that raising the foot loosens the grip of the members on the stock, and 5 a spring acting to hold the presser foot and its connected member in contact with the stock.

4. A machine of the class described, having, in combination, a knife, a plurality of 10 members constructed and arranged to grip the stock and feed it to the knife, a presser foot connected to one of said members in such manner that raising the foot loosens the grip of the members on the stock, and 15 means whereby the tension of the spring may be varied.

5. A machine of the class described, having, in combination, a knife, a feed roll, a feed disk coöperating with the roll to feed 20 the stock to the knife, and a presser foot connected to the feed disk in such manner that raising the presser foot raises the feed disk.

6. A machine of the class described, having, in combination, a knife, a feed roll, a feed disk coöperating with the roll to feed 25 the stock to the knife, a presser foot connected to the feed disk in such manner that raising the presser foot raises the feed disk, and yielding means acting to hold the presser foot and its connected disk in contact with the stock.

7. A machine of the class described, having, in combination, a rotary skiving knife, 30 a rotary feed roll, a vertically yieldable feed disk arranged to coöperate with the roll to feed the stock to the knife, and a presser foot connected to the feed disk in such manner that raising the foot from the 35 roll raises the disk.

8. A machine of the class described, having, in combination, a knife, an edge gage, means for feeding the work constructed and arranged to crowd the edge of the work 40 against the gage, and means responsive to curling of the edge of the work for controlling the feeding means.

9. A machine of the class described, having, in combination, a skiving knife, a feed 45 roll, an edge gage and a feed disk, rotatable in a plane substantially parallel to the plane of the work, adapted to coöperate with the

roll to feed the stock to the knife and arranged to hold the stock against the gage during the feeding movement.

55

10. A machine of the class described, having, in combination, a rotary skiving knife, a rotary feed roll, an edge gage located above the feed roll, and a rotary feed disk arranged to rotate in a plane substantially 60 parallel to the plane of the work to co-operate with the roll to feed the stock to the knife, the location of the disk with respect to the gage being such that the point on the disk which is nearest the gage 65 is moving in a direction to crowd the edge of the stock against the gage.

11. A machine of the class described, having, in combination, a skiving knife, a feed 70 roll, a feed disk coöperating with the feed roll to advance the stock to the knife, and an edge gage located over the axis of the feed roll, the axis of the disk being located in the rear of a vertical plane containing the axis of the roll.

75

12. A machine of the class described, having, in combination, a knife, an edge gage, a plurality of members constructed and arranged to grip the stock and feed it to the knife, one of said members acting to hold 80 the edge of the stock firmly against the gage, and means responsive to the curling of the edge of the stock for loosening the grip of the feed members.

13. A machine of the class described, having, in combination, a knife, an edge gage, a feed roll, means for crowding the edge 85 of the stock against the gage, and means responsive to the curling of the edge of the stock for decreasing the effectiveness of the 90 crowding means.

14. A machine of the class described, having, in combination, a knife, an edge gage for guiding the work to the knife, means including a rotary disk for feeding the 95 work, yielding means for holding the disk against the work, a presser arranged to bear upon the work close to the edge gage and connecting means between the presser and disk.

100

In testimony whereof I have signed my name to this specification.

HERBERT E. ENSLIN.
